(57) **CLAIM**

The ornamental design for a baby car seat cooling pad, as shown and described.

DESCRIPTION

FIG. 1 is a perspective view of a baby car seat cooling pad showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a front perspective view thereof, shown the state of use; and,

FIG. 9 is a front perspective view thereof, shown in a bent state.

The broken lines in FIG. 8 of the drawings depicting a baby car seat represent environment that forms no part of the claimed design.

1 Claim, 9 Drawing Sheets
